Primary Examiner — John A Voytek*(74) Attorney, Agent, or Firm* — HEMINGWAY & HANSEN, LLP; D. Scott Hemingway; Elizabeth P. Hartman(57) **CLAIM**

The ornamental design for a tire tread, as shown and described.

DESCRIPTION

FIG. 1 is a front perspective view of a tire tread of the present application;

FIG. 2 is a front elevation view thereof;

FIG. 3 is a right side view thereof, with the left side view being identical thereof;

FIG. 4 is an enlarged front perspective view of FIG. 1, showing a portion thereof;

FIG. 5 is an enlarged front elevation view of FIG. 2, showing a portion thereof; and,

FIG. 6 is an enlarged side view of FIG. 3, showing a portion thereof.

In the drawings, the broken lines depict environmental subject matter only and form no part of the claimed design. The tread pattern is understood to repeat throughout the circumference of the tire.

1 Claim, 6 Drawing Sheets(56)
